UNITED STATES PATENT OFFICE.

SIDNEY H. SHORT, OF LONDON, ENGLAND, ASSIGNOR TO WESTINGHOUSE ELECTRIC & MANUFACTURING COMPANY, A CORPORATION OF PENNSYLVANIA.

SAFETY APPARATUS FOR USE ON RAILWAY-CARS.

SPECIFICATION forming part of Letters Patent No. 761,417, dated May 31, 1904.

Application filed February 11, 1902. Serial No. 93,516. (No model.)

To all whom it may concern:

Be it known that I, SIDNEY H. SHORT, a citizen of the United States, and a resident of London, in the county of Middlesex, England, have 5 invented certain new and useful Improvements in Safety Apparatus for Use on Railway-Cars, of which the following is a specification.

The present invention relates more particularly to apparatus adapted for use on electric-railway cars, such as are operated on the trolley system and are provided with passenger-seats on the top of the car.

The object of the invention is to prevent 15 danger to passengers occupying these seats by reason of the trolley becoming charged with electricity, the means of prevention being an audible or other alarm or signal calling the attention of the motorman or conductor to the 20 dangerous condition of the pedestal.

It is well known that in practice the trolley-pole is normally insulated upon the trolley-pedestal and that the trolley-wheel is normally insulated from the trolley-pole. If, however, 25 these insulations break down, the pressure of the trolley-line is communicated to the trolley-pedestal, thus bringing about a condition which puts the passengers at the top of the car in a position of danger. When such a condition supervenes, the signal provided for by 30 the present invention is made, the motorman or conductor warns the passengers and removes them from danger, and the car is returned to the depot to have the defective insulation rectified.

My invention will be fully understood by reference to the accompanying drawing, which is a diagram of an alarm system adapted to provide the protection indicated in the foregoing.

As a means for carrying my invention into effect I show a locked box 1, in which is mounted a fuse 2, of fine copper wire, inclosed within a tube 3, of porcelain or other good heat-re-

sisting material. The upper end of the fuse 45 is permanently attached to a brass cap 4, which is in connection with the trolley-pedestal 5; while the lower end of the fuse passes loosely through the bottom 6 of the tube 3 and is attached to the free end of the weighted lever 7. 50 The lever 7 is pivoted at 8, and the pivot end is connected by a grounding-wire 9 with the car-wheel 10 and the rail 11.

Below the free end of the lever 7 is located a spring 12, with which the said end is adapted 55 to come into contact when the lever is released, as by the breaking or fusing of the wire 2. This wire melts or fuses when the pressure of the trolley-line is communicated to the trolley-pedestal, whereupon the lever 7 falls and 60 comes into contact with the spring, thereby closing the circuit of a local battery 13, including a vibrating bell 14. This bell continues to ring until the box 1 has been unlocked, a new fuse substituted, and the pivoted lever 7 65 restored to its normal position.

The foregoing are the parts essential to my alarm system and its successful operation.

For the sake of completeness I may add that a generator for the trolley system is indicated 70 at 15, the trolley-wire at 16, and the trolley-arm at 17.

I claim as my invention—

1. The combination with an electrically-propelled vehicle, of a supply-circuit extending 75 along the way of the vehicle, a conducting-support upon the vehicle, a traveling contact carried by the said support and making contact with the said supply-circuit, the said conducting-support being normally insulated from the 80 traveling contact, a conducting-circuit connecting said support with the return-circuit of the vehicle, and an alarm or equivalent device brought into operation by currents traversing said conducting-circuit. 85

2. In an electric-railway system, a trolley-wire, a trolley-base normally insulated therefrom, a local circuit extending from the trolley

2
to ground and containing a fuse, a pivoted weighted arm mechanically connected with the said fuse, and a circuit-terminal located in the path of movement of the said weighted arm, 5 the said arm and the said terminal being included in a local signaling or alarm circuit.

Signed at London, in the county of Middle-

sex, England, this 31st day of January, A. D. 1902.

SIDNEY H. SHORT.
